STACKABLE STORAGE DRUM

Robert E. Marsh, Los Alamitos, Calif., assignor, by
mesne assignments, to Union Carbide Corporation,
New York, N.Y.

Filed Sept. 17, 1962, Ser. No. 71,711

Term of patent 7 years

(Cl. D58—3)

FIG. 1 is a perspective view of a stackable storage drum showing my new design;

FIG. 2 is a side elevation thereof;

FIG. 3 is a top plan view thereof; and

FIG. 4 is a bottom plan view thereof.

The characteristic feature of my design resides in the combination on a stackable storage drum of the configuration disclosed of the raised complementary spaced arcuate stacking elements on the top, together with the offset fittings disposed in the channel therebetween, all as shown.

I claim:

The ornamental design for a stackable storage drum, substantially as shown and described.
